COOLER AND DISPENSER UNIT FOR USE IN
MAKING COLD BEVERAGES, DRINKS,
SOUPS AND THE LIKE

William C. Christine, Catasauqua, and Joseph E. Pierce,
Allentown, Pa., assignors to Allen Electronics, Inc.,
Allentown, Pa., a corporation of Pennsylvania

Substituted for abandoned design application Ser. No.
81,392, Aug. 21, 1964. This application Oct. 22, 1965,
Ser. No. 358

Term of patent 14 years

(Cl. D2—3)

FIG. 1

FIG. 2

FIG. 3

FIG. 4

FIG. 5

FIG. 1 is a front perspective view of the cooler and dispenser unit for use in making cold beverages, drinks, soups and the like, showing our new design.

FIG. 2 is a side elevational view thereof.

FIG. 3 is a top plan view thereof.

FIG. 4 is a rear elevational view thereof.

FIG. 5 is a bottom plan view.

The undisclosed side is substantially the same as the side shown in FIG. 2.

We claim:

The ornamental design for a cooler and dispenser unit for use in making cold beverages, drinks, soups and the like, as shown and described.
